No. 754,977.

UNITED STATES PATENT OFFICE.

FRANK E. DOPHEIDE, OF PALMYRA, ILLINOIS.

JAR-CLOSURE.

SPECIFICATION forming part of Letters Patent No. 754,977, dated March 22, 1904.
Application filed April 30, 1903. Serial No. 155,009. (No model.)

To all whom it may concern:

Be it known that I, FRANK E. DOPHEIDE, a citizen of the United States, residing at Palmyra, in the county of Macoupin and State of Illinois, have invented a new and useful Jar-Closure, of which the following is a specification.

The invention relates to improvements in jar-closures.

10 The object of the present invention is to improve the construction of jar-closures, more especially that shown and described in Patent No. 702,412, granted to me the 17th day of June, 1902, and to lessen the cost of construction and enable a jar to be closed and sealed with greater ease and without liability of the hands of the operator coming in contact with the heated contents of a jar.

15 A further object of the invention is to enable the packing-ring to be carried by the plug instead of being fitted within the neck of the jar, whereby the plug will be interposed between the hands of the operator and the contents of the jar while closing and sealing 25 the same.

20 The invention also has for its object to increase the effectiveness of the sealing action of jar-closures and to enable a perfect seal to be obtained irrespective of the usual imperfection in the form of the mouths of jars and caps or plugs.

25 Furthermore, the invention has for its object to provide a structure in which an elastic packing will be interposed between the walls of the neck of a jar and the side faces of a closure-plug and which will prevent the packing-ring from slipping downward too far during the sealing operation and interfering with the same.

30 With these and other objects in view the invention consists in the construction and novel combination and arrangement of parts hereinafter fully described, illustrated in the accompanying drawings, and pointed out in 35 the claims hereto appended, it being understood that various changes in the form, proportion, size, and minor details of construction within the scope of the claims may be resorted to without departing from the spirit or

sacrificing any of the advantages of the invention.

In the drawings, Figure 1 is a vertical sectional view of a portion of a jar provided with a closure, constructed in accordance with this invention, the parts being arranged preparatory to closing and sealing the jar. Fig. 2 is a similar view illustrating the position of the parts when the jar is closed. Fig. 3 is a detail perspective view illustrating the construction of the neck of the jar. Fig. 4 is a similar view of the plug. Fig. 5 is a vertical sectional view illustrating a slight modification of the invention. Fig. 6 is a similar view illustrating another modification of the invention. Fig. 7 is a sectional view of the plug and the elastic packing-ring, illustrating the arrangement of the latter before the same is applied to a jar.

Like numerals of reference designate corresponding parts in all the figures of the drawings.

1 designates the upper portion or neck of a jar provided with an inner vertical face 2 and having an annular recess 3, forming an open seat for a packing-ring 4, which during the operation of sealing is carried by a plug 5, whereby the plug is interposed between the hand of the operator and the heated contents of the jar and is adapted to form a guard to prevent the operator from being injured by the said contents. The plug 5 is preferably hollow, as shown, and it is provided on its exterior with upper and lower shoulders 6 and 7, formed by reducing the intermediate and lower portions of the plug and presenting annular bevel-faces to the packing-ring. The packing-ring is constructed of fine rubber and is tapered, as indicated in Fig. 1, and it fits on the lower reduced end of the plug and is carried by the latter instead of being arranged in a groove of the neck of the jar, as set forth in said patent, thereby obviating the necessity of introducing the fingers into the mouth of the jar after the latter has received its contents. The lower reduced end of the plug receives sufficient of the packing-ring to permit a portion of the same to be introduced into the neck of the jar below the seat thereof before the vertical engaging face 8, which lies between the upper and lower

shoulders, comes in contact with and compresses the packing-ring between it and the vertical face of the neck of the jar. A sufficient amount of the rubber packing-ring is forced into the jar to prevent any displacement of the ring and to insure a close connection and a perfect seal, and as the plug is forced inward the face 8 slips downward over the inner face of the packing-ring, which is further compressed. The plug is forced inward until the upper shoulder comes in contact with the upper portion of the packing-ring and forces the same against the seat, thereby further compressing the elastic packing-ring and producing an air-tight joint or seal at the said seat. By this construction a positive air-tight connection and a perfect seal is provided irrespective of the imperfections and inaccuracies present in such jars.

20 The plug is provided at its upper end with a head or enlargement 10, and the distance between the upper shoulder and the lower face of the head or enlargement is greater than the depth of the annular recess 3 to space the head or enlargement from the neck of the jar when the latter is sealed; as shown in Figs. 2 and 5. A knife-blade or similar tool may be readily inserted in the intervening space 11 between the lower face of the enlargement 10 and the upper edge of the jar. The plug is readily removed by lifting one side and thereby permitting air to enter the vacuum within the jar. The jars are sealed while their contents are heated and while the space between the contents and the plug is filled with steam or vapor, and as soon as the jar cools the vapors condense, thereby forming a vacuum and drawing the plug more tightly against the seat of the jar.

30 When the plug is forced inward into the neck of the jar, the lower or inner portion of the elastic packing-ring is frictionally engaged and compressed by the plug as soon as the lower shoulder passes the seat. This operation causes the plug to slip through the packing-ring, which conforms to the configuration of the neck of the jar, and when the upper shoulder engages the packing-ring the latter is spread over the seat, and the jar is effectively sealed. The sealing action of the device may be increased by providing an upwardly-projecting beveled rib 12, as illustrated in Fig. 3. The oppositely beveled or tapered rib 12 is adapted to be partially embedded in the lower face of the upper or outer portion of the elastic packing-ring, and the latter is tightly compressed against the jar and the beveled face of the upper shoulder and a positive seal is provided. This construction is especially adapted for receptacles having more or less irregularities in the engaging faces of the neck and the plug.

In Fig. 6 of the drawings is illustrated another modification of the invention, in which

an elastic packing-ring 13 is employed, and this packing-ring, which is approximately L-shaped in cross-section to provide vertical and horizontal portions when it is applied to a jar, is curved at 14, as shown in Fig. 7 of the drawings. The jar 15 is constructed substantially the same as that shown in Fig. 1, and the plug 16 has an upper horizontal shoulder 17 extending outward over the seat of the jar and adapted to compress the upper or outer portion of the elastic packing-ring against the same. The lower portion of the plug is constructed similar to that before described, and the packing-ring is placed on the same and introduced into the jar, as before explained. The upper or outer portion of the packing-ring is adapted to lie flat against the shoulder or seat of the jar, and the upper horizontal shoulder of the plug is preferably provided with a depending rib 18, which is embedded in the upper face of the elastic packing-ring, as illustrated in Fig. 6 of the drawings. This construction is especially designed for jars having more or less nicks, notches, or similar imperfections at the shoulder or seat produced while the jars are being manufactured. The flat upper or outer portion of the elastic packing-ring is adapted to cover and effectually close such imperfections and will enable a perfect sealing of the jar to be obtained.

Having thus fully described my invention, what I claim as new, and desire to secure by Letters Patent, is—

1. The combination with a receptacle having an upright engaging portion and provided at the top thereof with a seat, of an elastic packing-ring, and a plug having a lower reduced portion carrying the packing-ring in applying the same to the receptacle, said plug being also provided with upper and lower shoulders arranged at an inclination, the intermediate portion between the shoulders being vertical and adapted to compress the packing between it and the engaging face of the receptacle and the upper shoulder of the plug being adapted to compress the packing-ring against the seat of the receptacle, substantially as described.

2. The combination with a receptacle having an upright engaging face and provided with a shoulder or seat, of a packing-ring, and a plug having a packing-ring-receiving portion and provided with an upright engaging face and having a shoulder at the top thereof for forcing the packing-ring against the shoulder or seat of the receptacle, one of the parts being provided with a beveled rib for engaging the elastic packing-ring, substantially as described.

3. The combination with a receptacle provided with an interiorly-arranged horizontal seat and having a vertical engaging portion beneath the same, a packing-ring constructed of thin flat elastic material, and a plug pro-

vided at the top with an annular enlargement forming a head and extending over the upper edges of the receptacle, said plug having a lower reduced portion for carrying the packing-ring and provided with upper and lower inclined shoulders, the intermediate portion between the shouluers being vertical and arranged to compress the packing between it and the vertical engaging face of the receptacle, and the upper shoulder being arranged

to compress the packing-ring against the seat, substantially as described.

In testimony that I claim the foregoing as my own I have hereto affixed my signature in the presence of two witnesses.
